UNITED STATES PATENT OFFICE

FRANK MAGIDSON, OF PITTSBURGH, PENNSYLVANIA, ASSIGNOR TO PITTSBURGH TAG COMPANY, OF PITTSBURGH, PENNSYLVANIA, A CORPORATION OF PENNSYLVANIA

TAG FASTENER

Application filed November 5, 1929. Serial No. 404,883.

This invention relates to fasteners and more particularly to fasteners adapted for use in attaching tags or other identifying media or indicia temporarily to articles or materials.

An object of the invention is the provision of a fastener which will effectively grip and attach itself to the article or material to be identified.

10 Another object of the invention is the provision of such a fastener which will not damage the article or material.

A further object is the provision of a fastener adapted for relatively hard or thick 15 articles or materials and especially for snapping on to wires, cords and the like without first opening the same manually.

A further object is the provision of a fastener readily and inexpensively formed 20 from a single piece of wire.

A still further object is the provision of a fastener which is easily secured to or detached from the associated article or material.

25 Other and further objects and advantages will either be apparent hereinafter or will be pointed out as the description proceeds.

In the accompanying drawings, wherein like numerals refer to similar parts throughout the several views:

Figure 1 is an elevation of a fastener associated with an identifying tag; and Figure 2 is a perspective elevational view; and Figure 3 is an edge view of the same.

35 Referring in detail to the drawings, the fastener comprises a single piece of wire 1 bent intermediate its ends, but not at its midpoint, to form a shorter leg 2 and a longer leg 3, which legs extend parallelly for the greater part of the length of the fastener.

40 At 4, the legs converge rapidly toward one another and cross at 5. At 5, however, the longer leg 3 is bent back upon itself over the shorter leg 2 so that it extends substantially

45 coextensive to and parallel with its own converging portion 4 to form a guiding and limiting oblique loop 6, in which the other leg may operate, which loop is completed by rebending leg 3 back upon itself again so

50 that it resumes the original direction to the

point 5. Thereafter both legs diverge as at 7 until substantially the original or desired width is obtained, whereupon both legs bend acutely inwardly and downwardly as at 8 below a line connecting their highermost 55 points until their beveled ends meet at 9.

The fastener is, of course, passed through any suitable tag or identifying ticket 10 before the above named bends are made and as the wire is bendable or resilient, shorter leg 60 2 may be temporarily displaced as shown by the dotted lines.

This displacement is unusually simple and easy due to the angled ends 8 and the general arrangement of the parts. The fastener 65 may be merely pushed against the wire, cord, or the like with the result that the meeting edges are forced apart the required distance so that the wire, cord, or the like, passes therebetween and the ends snap back into 70 place inasmuch as by their construction they are constantly urged into contacting position.

The loop 6 guides and limits the displacement of leg 2 and prevents the elastic limit 75 of the material from being exceeded as well as avoiding lateral movement of the parts which would not so well accomplish the desired end.

To detach the tag and fastener, a simple 80 grasping of the legs 2 and 3 between the thumb and finger of one hand and gently squeezing the same will displace leg 2 and open the ends at the point 9.

The invention has proved of exceptional 85 merit for use in shipping or parcel post departments, particularly where it is desired to attach the tags speedily without the necessity of time-consuming manual operations.

The invention may also be used on hard 90 surfaces like parchments and the angled ends give a better and non-slipping grip thereon.

It is clear that a fastener without the 95 sloping or inclined ends 8 is totally unable to perform the present operations.

I have shown a preferred form of my fastener and have described the same but such is to be deemed illustrative and not limitative 100

except as set forth in the subjoined claims. The material may be any suitable and preferably resilient metal but other substances may be successfully utilized. The size, direction and extent of loop 6 may vary to suit the circumstances and the breaking or fatigue point of the substance used so that such point may not be exceeded. The exact pitch of the slope of the downturned ends may be varied, as likewise may the extent or width of the various portions. Preferably, a single piece of wire is used but a plurality of pieces could be used if necessary. The complete fastener clearly lies substantially in a single plane.

What I claim as new and desire to secure by Letters Patent is:

1. A device of the character described consisting of a single piece of wire bent intermediate its ends to form legs of unequal length substantially parallel for the greater part of the extent of the finished fastener, the legs thereafter converging and crossing, the longer leg being bent over the shorter one at the point of crossing and extending back coextensively with and parallel to its own converging portion, thereafter again reversing and following the original direction, thus forming a guiding and limiting loop in which the shorter leg operates, said legs thereupon diverging to a width approximately that of the parallel legs, subsequently curving inwardly and downwardly into contact below a line connecting the highermost points.

2. A fastener consisting of a unitary piece of resilient wire bent intermediate its ends at a point to one side of the center thereby forming a shorter and a longer leg, said legs extending parallel for the greater portion of the length of the finished fastener, the legs thereafter converging and crossing, the longer leg being bent over the shorter at the point of crossing and extending downwardly coextensive with and parallel to its own converging portion, thereafter curving back upon itself again and following the original direction to the point of crossing aforesaid, thus forming a limiting and guiding loop in which the shorter leg operates, both legs thereupon diverging to a width approximately that of their parallel portions and subsequently bending at an acute angle inwardly and downwardly into contact below a line connecting their highermost points, the ends of the wire being beveled and the whole fastener lying substantially in a single plane.

3. A fastener having contacting ends adapted to be opened temporarily by contact with the article to which it is to be attached and including two legs one of which is looped about the other to form a limiting guide therefor, the legs thereafter diverging and subsequently bending downwardly into con-

tact below a line connecting their highermost points.

In testimony whereof, I have hereunto subscribed my name this 4th day of November, 1929.

FRANK MAGIDSON.
